UNITED STATES PATENT OFFICE.

EDWARD F. PICKETT, OF BUFFALO, NEW YORK.

DESIGN FOR A NIPPLE FOR BICYCLE-PUMPS.

SPECIFICATION forming part of Design No. 31,562, dated September 26, 1899.

Application filed August 26, 1899. Serial No. 728,628. Term of patent 14 years.

To all whom it may concern:

Be it known that I, EDWARD F. PICKETT, a citizen of the United States, residing at Buffalo, in the county of Erie and State of New York, have invented and produced a new and original Design for Nipples for Bicycle-Pumps, of which the following is a full, clear, and exact specification, reference being had to the accompanying drawings, in which—

Figure 1 is a sectional view of a nipple, showing my design. Fig. 2 is a side elevation. Fig. 3 is a front view.

As illustrated, the leading feature of my design is in the configuration of the nipple and particularly in the form of the head or front end thereof. The nipple has a central portion A, a headed end B, a flange C in rear

of the portion A, and a plain cylindrical extension D. The head B is of rounded conical shape, ending in the central bore E at one end ²⁰ and a square shoulder F at the opposite end. The flange C projects beyond the periphery of the part A. The rear extension D is threaded to engage the end of the pump.

What I claim is—

The design for the nipple of a bicycle-pump, as herein shown and described.

In testimony whereof I affix my signature in presence of two witnesses.

EDWARD F. PICKETT.

Witnesses:

HENRY E. COOPER,
R. E. OURAND.
